SCARIFYING TOOTH AND HOLDER

Arthur B. Wilson, East Lansing, Mich.

Application August 30, 1934, Serial No. 742,085

7 Claims. (Cl. 262—33)

This invention relates to a scarifying tooth for road work and a holder therefor. More particularly it relates to a replaceable point for a scarifying tooth and a holder which allows of the ready changing of points while holding the points securely in position during operation.

It is well known that scarifying teeth are worn away very rapidly. In my prior patent on Scarifying tooth, No. 1,859,350, issued May 24, 1932, I provided a construction of a point which made it possible to wear away a considerable length of a tooth while maintaining the point sufficiently sharp for effective work, but even such a construction wears away quite quickly under the trying conditions of digging up old roads and thus the teeth must be changed frequently.

It is fairly obvious that a considerable saving may be made by discarding only the worn off end of the tooth and so much as is necessary to hold it in place rather than a longer, two-ended tooth, such as has been used frequently in the past. However, it is very difficult to devise a practical holder which will endure the necessary strain and will hold the tooth in place during its operation and will at the same time release the point readily when it is desired to change the points.

It is the purpose of my present invention to overcome these difficulties.

In the accompanying drawings forming a part of this specification, Figure 1 discloses a carrier beam with a plurality of teeth mounted therein and embodying one form of my invention; Figs. 2 and 3 are details of the construction shown in Figure 1 and illustrating how the points may be removed; Fig. 4 is a detail figure disclosing another embodiment of my invention; Fig. 5 is another detail view disclosing still another embodiment of the invention; Figs. 6 and 7 are sectional views on lines 6—6 and 7—7, respectively, of Fig. 5; Fig. 8 is a detail view of a portion of the construction shown in Fig. 5, viewed from the right of that figure and partly broken away.

In Figure 1 there is shown a carrier beam 10 in which there are mounted a plurality of tooth holders 11. In the construction shown each holder 11 is provided with a slot 12 above beam 10 and a rod 13 is run through these slots and has thereon wedges 14 so that, when in the position shown in the drawings, the tooth holders are wedged upward to their highest position, as will be explained more fully later. If desired, springs 15 may be provided upon each of the wedges 14, but one spring 15 being shown in the drawings. These springs insure that the holders will be held

to their highest position even if there are some slight irregularities. This is preferable, although slight play in the holder is not serious.

Each holder 11 has below the beam a head 16 which carries a replaceable tooth 17. In the construction shown in Figure 1, the tooth is provided with a front member or plate 20 which does the scarifying and with a plurality of braces 21, 22 which hold the front plate in position, but are bent back out of the way as the front plate 10 is worn off, as fully described in my prior patent identified above. At the top of the tooth portion of the point, there is a flange 23 above which a holding portion 24 of the point extends into the head 16, which is provided with a suitable socket 15 25 therefor.

In the construction shown in Figure 1, this holding portion 24 comprises a front member 26 and a rear member 27 between which the metal is cut away at 28. The metal is needed at 26 20 and 27 to hold the point firmly in place and the cut-away portion at 28 is for the sake of lightening the construction.

At the upper end of member 26 there is a forwardly projecting lug 29 which rests upon the front 30 of the head 16. Above head 16 there is a clamping member 18 which holds tooth 17 in place. This clamping member 18 is provided with a portion 31 which slides longitudinally of the holder 11 and with a wedge member 32 which 30 extends downward at the front of member 11 and is adapted to wedge behind the upper portion 33 of lug 29 so that, when clamping member 18 is in the position in which it is shown in Fig. 2, it securely holds the point in place. A shield 34 35 extends downward from the front of clamping member 18 so as to shield the joints around part 29 from the entrance of dirt during the operation of the device. It will be seen from an inspection of Fig. 2 that flange 23 likewise fits against the bottom of head 16 and prevents the entrance of dirt into socket 25 about member 24.

It is quite necessary to provide means for preventing the entrance of dirt into the socket during the operation of the device as otherwise such dirt will become packed into the joints so securely that the removal of the point becomes a matter of extreme difficulty.

It will be readily seen that when it is desired to change the points the member 13 may be moved 50 to the right in the direction of the arrow in Figure 1 which will allow the lowering of holders 11 so that clamp 18 may be slipped up with relation to head 16 and release the point. As soon as wedge 32 rises above the upward extension 33 55

of lug 29, the upper end of the tooth may be 5 swung backwards, as shown in Fig. 3, and the point is readily slipped from the holder and a new one placed in the holder. When all, or as many as desired, of the points have been replaced in this way, the holders 11 are raised so as to bind clamp 18 between head 16 and the bottom of beam 10, thus preventing the releasing of the points.

10 While the manner of raising and lowering the holders 11, which has been illustrated, is a convenient and practical way, it is obviously not the only way in which it can be done and any other means for fixing the holders in their elevated position and releasing them, when desired, for removal of the points may be substituted and retain a number of advantages of the invention.

15 It is quite important, however, that the fastenings which hold the points in place shall be 20 releasable primarily from a point above the bottom of the carrier beam so that the releasing device is not rendered inoperative or difficultly operative by the contact with dirt to which parts below the beam are subjected.

25 In the construction just described it will be noted that the point is held in place against the chief force to which it is subjected by portions 26 and 27, and that lug 29 holds it securely against longitudinal movement, but, of course, 30 there is much less force applied in this direction than in a lateral direction. When member 11 is lowered, clamp 18 can simply slip upward on that member and release the point, and the joints which constitute this releasing construction are 35 completely protected against the entrance of dirt so that the releasing operation can be very easily accomplished.

30 In Figs. 4 and 5 there are shown two possible variations which retain some of the advantages 40 of the construction described above. In Fig. 4 the holder 11 is provided with a modified head 16' adapted to receive the holding portion 24' of a point 17'. The upper end of member 24' is provided on its front side with a notch 36 in 45 which there enters a tooth 37 on clamping member 18'. The rear of head 16 is provided with a cam 38 against which a cross member 39 at the back of clamp 18' works. It will be readily seen 50 that, when the parts are in the position in which they are shown in Fig. 4, the tooth is firmly held in position and is prevented from longitudinal movement by the tooth 37 which is securely held in notch 36 so long as clamping member 18' is held in the position in which it is shown in that 55 figure. When member 11 is lowered, it will be seen that the back side of clamp 18' may be raised, as indicated in dotted lines in Fig. 4, and as part 39 slips up cam 38, it allows the forward movement of the clamping member so as to release 60 tooth 37 from notch 36 and allow the removal of a tooth.

65 In Fig. 5 the construction involves a slight modification of the socket within beam 10', as shown. The member 11 is provided with a modified head 16'' on which the point 17'' is mounted. In this case the bottom of the holder 16'' is provided with a dove-tail groove 40 in which a T-shaped flange 41 on top of point 17'' slides. When in operating position, the tooth is 70 slid back until the upward extension 24'' rests against the front of head 16''. The upper end of portion 24'' terminates in an extension 42 having a head 43 which rests upon lugs 44 extending outward from the front of head 16''. This 75 arrangement assists in holding the tooth against

longitudinal movement, but, of course, is not absolutely necessary since such longitudinal movement is prevented by the connection 40, 41. A clamping member 45 slides on the front of the head 16'' and in operative position passes from 5 in front of extension 42 around lugs 44 and has rear flanges 46 sliding in grooves 47 in head 16'.

When holder 11 is lowered, it will be readily seen that clamping member 45 may be raised so as to allow the point to move forward. When 10 released in this manner, the tooth may be slid forward as indicated by dotted lines in Fig. 5, and this movement may be continued until portion 41 is released from the groove 40 so that the point may be removed. 15

It will be seen that each of the devices described above has certain features in common. In the first place the tooth is held in position by a clamp which in turn is held in position between a head on member 11 and the beam. The only 20 thing necessary for the release of the point is the downward movement of holder 11 which allows the relative upward movement of the clamping member. Likewise in each case the downward pressure of the beam and head upon the tooth 25 rests upon the upward extension of the tooth and upon the flange of the tooth so that it is not transmitted through the clamping device except as the clamping device rests squarely on the head.

The forms which are shown in Figs. 1 and 4 30 have the further advantage that they may be readily applied to beams now on the market and in which solid teeth of the old type have been mounted where the downward extending point is worn away until it becomes so blunt as to be no 35 longer useful and then the tooth is turned over and the other end used in the same way. Thus the new construction shown in Figs. 1 and 4 may be readily applied to many machines now in use. 40

While there are certain advantages in the modifications shown, it will be readily understood that other changes may be made within the scope of the appended claims while retaining some of the advantages of this invention. 45

What I claim is:—

1. In scarifying apparatus, a carrier, a holder having a shank slidable vertically in the carrier, and a head below the carrier, a tooth mounted in the head, a clamping member slidable on the shank between the head and carrier securing the tooth in the head when the head is held in its closest position to the carrier and releasing the tooth when the head is lowered, and releasable means to secure the shank in its upper 55 position in the carrier.

2. Apparatus in accordance with claim 1, and in which the last said means is located above the carrier.

3. In scarifying apparatus, a carrier, a holder comprising a shank slidable vertically in the carrier and a head beneath the carrier, there being a downwardly opening socket in the head, a tooth having a securing portion fitted into said socket and a flange around the bottom of said portion and fitting against the bottom of the head around the socket, releasable means for securing the shank in its raised position in the holder, and means, secured in position by the holding of the shank in its upper position, for holding the securing portion of the tooth in the socket. 70

4. Apparatus in accordance with claim 3, and having said releasable means above the carrier.

5. Apparatus in accordance with claim 3, and having the upper end of said socket opening 75

- through the front of the head and the upper end of the securing portion of the tooth hooked onto the lower edge of said opening, and the last said means comprising a member slideable upon the shank between the head and the carrier and having a wedge projecting downward back of said opening and a cover plate projecting downward in front of said opening.
5. In road scarifying apparatus, a carrier, a plurality of holders each having a shank slideable vertically in the carrier and a head below the carrier, means for simultaneously raising said shanks in said carrier and securing them releasably in their raised position and for simultaneously releasing them for lowering a limited amount, a tooth in each head, and means holding the teeth in the heads when the shanks are raised and releasing the teeth when the shanks are lowered.
6. In road scarifying apparatus, a carrier, a plurality of holders each having a shank slideable vertically in the carrier and a head below the carrier, means for simultaneously raising and lowering the shanks in said carrier and securing them releasably in their raised position and for simultaneously releasing them for lowering a limited amount, a tooth in each head, and means holding the teeth in the heads when the shanks are raised and releasing the teeth when the shanks are lowered.
7. Apparatus in accordance with claim 6, and having said raising and lowering means mounted above the carrier.
10. ARTHUR B. WILSON.
